UNITED STATES PATENT OFFICE.

JAMES E. YORK, OF NEW YORK, N. Y., ASSIGNOR TO YORK ROLLING PROCESS COMPANY,
A CORPORATION OF NEW YORK.

STEEL-ROLLING APPARATUS.

1,001,116.

Specification of Letters Patent. Patented Aug. 22, 1911.

Application filed February 16, 1906. Serial No. 301,424.

To all whom it may concern:

Be it known that I, JAMES E. YORK, a citizen of the United States, residing in the borough of Brooklyn, county of Kings, city and State of New York, have invented certain new and useful Improvements in Steel-Rolling Apparatus, of which the following is a specification.

In my application for Patent No. 274,516, filed August 17, 1905, I have described the forming or spreading of a flange upon an elongated shape by rolling the same laterally, and suitable apparatus therefor.

The present invention provides certain improvements of such apparatus and certain other improvements referred to in detail hereinafter.

The accompanying drawings illustrate embodiments of the invention.

Figure 1 is a longitudinal section of a bed carrying rails ready for the rolling operation. Figs. 2 and 3 are similar sections of a style of bed arranged to bend a flange simultaneously with the forming of the same, Fig. 2 showing the rails in position to be clamped for rolling, and Fig. 3 showing the rails after being clamped. Fig. 4 is a similar section showing a method of bending the upper flange; Fig. 5 is a plan of the feeding apparatus; Fig. 6 is an elevation of the end of one of the plungers.

The principal features of the apparatus are a roll A, which may be vertically adjustable and rotatable as in ordinary rolling mills, and one or more beds or carriers arranged to reciprocate beneath the roll A. Elongated shapes, such, for example, as the railway rails B, are carried by the bed in positions transverse to the direction of its movement, so that the exposed portions of said shapes (the heads of the rails in the present instance) are spread laterally upon the bed as a support to form the flange, or to spread a flange or head originally presented. The elongated shapes are introduced preferably by shoving them endwise into their grooves. For greater ease in introducing and withdrawing the elongated shapes the bed is composed of a number of separable sections C mounted upon a substantial base D, the sections being free to move toward each other, that is to say, longitudinally of the bed as a whole, and being held against lateral movement by any suitable mechanism.

After the rails are introduced into the grooves formed by the spaces between the sections, the latter are pressed together so as to engage the webs of the rails or similar shapes. The roll then passes backward and forward, the rails being preferably softened by previous heating, until the heads of the rails are spread to flanges of the desired shape. This spreading is accompanied necessarily by a considerable downward pressure or draft of the roll. The pressure upon the work is transmitted directly to the overhanging end portions D of the movable sections. In my previous application it was proposed to leave the bases E of the rails without support beneath them so as to insure that the heads F of the rails should rest squarely upon the tops of the sections C, and also for the purpose of causing a slight downward curving of the center of the flange resulting from the rolling of the head.

According to my present invention I propose to wedge the bases E of the rails tightly between the base D of the bed and the overhanging portions D' of the sections C, and at the same time to wedge the overhanging portions C' of the sections as closely as possible between the tapering upper face of the rail base E and the under face of the head F. This will of course necessitate the use of sections C differently proportioned to fit the different sizes of rails worked upon, but as rail designs are very well standardized this will not involve any particular difficulty. Such a machine is more durable than the machines in which the bases of the rails are in a free space. The pressure of the roll is necessarily very great, and the overhang of the portion C' of each section is so great in proportion to its depth, and the softening of the metal of the bed by the heat communicated from the hot rails is so great that there is a material bending downward of the overhang E' after the machine has been in use for a comparatively short time. By the arrangement shown the overhang C' is pressed closely against the top face of the base E of the rail, and the latter in turn is pressed firmly against the base D of the bed so that the overhang C' is supported practically as well as if it were solidly connected in a vertical line with the base D of the bed. The durability of the machine is therefore practically as great as if there

were no bending strain upon the overhang. Furthermore, the sections C being loose upon the bed there is a tendency of these sections to tilt as the roll passes from one side to 5 the other of a section. Where the overhanging edges of the sections are supported in the manner described, there can be no such tilting, and the work can be rolled much more accurately to desired dimensions. 10 Each section being supported at its opposite sides there is really no need for a support at the center except to hold up the sections while the rails are being introduced into their grooves. Another advantage flowing 15 from this arrangement is in the more uniform heating of the sections. With the previous construction of the bed the section C came into intimate contact with the hot rails only along the upper portions of the sections. 20 These also are the portions which are most heated by the operation of rolling. It is practically essential to heat the entire rail in order to get the head hot, and when such a heated rail is clamped between the sections 25 in the manner shown the heat in the bases of the rails is transmitted to the lower portions of the sections C so that these sections are heated nearly uniformly at top and bottom, and the distortion which was previously 30 observable no longer occurs.

The clamping movement of the sections of the bed upon the bases of the rails may be taken advantage of also to give to such bases a curved cross-section, which is thought desirable in railway ties. The bases of the rails being already hot are easily bent between the properly shaped surfaces, so that in point of time the bending of the lower flange and the converting of the upper head 35 into a flange cost no more than the single operation of rolling the head into a flange. For this purpose it is only necessary to form convex ribs G upon the base D of the bed and corresponding concaves or grooves H 40 upon the under edges of the overhanging portions C' of the sections C. When the sections are then pressed together and have assumed their determined positions with the rails between them the bases of the rails 45 will be curved in the manner indicated at E' in Fig. 3.

The desired curvature of the upper flange may be obtained in the operation of rolling either by suitably concaving the upper face 55 of the sections of the bed, or even by a simple manipulation of the roll, as I have discovered by experiment. Fig. 4 illustrates this operation. When the flange F' has been rolled out quite thin and a heavy draft is 60 put upon the roll A, the edge of the flange F rises as the roll passes off it, this rising being probably due either to the spring of the metal of the flange or to adhesion to the roll. By putting only a light draft upon 65 the roll, or no draft other than its own

weight, the flange may be flattened again. Therefore by merely operating the wheel controlling the draft the flange may be made curved or flat as desired. I do not claim this method of curving the upper flange in 70 the present application, but I am not to be understood as thereby abandoning my right to claim the same in a separate application. I propose to employ also a new mechanism for feeding the rails or similar shapes to 75 the bed upon which they are rolled. Figs. 5 and 6 illustrate the mechanism.

The bed, which I characterize as a whole by the reference letter J, has a feeding table K arranged alongside of it when the bed is 80 in one or the other of its extreme positions. The table carries the rails B from the furnace where they are heated to a position alongside the bed, and they are then shoved into the grooves of the bed. Various mechanisms or arrangements for handling the feed table and moving the rails therefrom may be utilized. I propose to mount the table upon a pair of rails L so that it may 85 be slid or rolled by hand or by gravity, or by any suitable power from its position alongside the bed, to a position shown in dotted lines alongside a furnace M. The rails are withdrawn from the furnace by 90 tongs or other suitable mechanism, and laid upon the bed, preferably in positions determined by breaks in the ribs N formed on the surface of the bed, these ribs serving as 95 guides to hold the rails in line with the grooves in the bed J, so as to facilitate their entrance into said grooves.

For transferring the rails from the table K to the bed, I propose to use hydraulic apparatus which shall push the rails endwise with a positive pressure as distinguished from the frictional grip in the mechanism shown in my prior applications above referred to. The hydraulic mechanism for example may consist of one or any suitable number of cylinders O mounted 100 upon a suitable base and carrying piston rods P, at the ends of which are fingers Q 105 engaging the ends of the rails and pushing them positively in the desired direction. A cylinder O may be provided for each pair 110 of rails, in which case a yoke R is formed on the end of the piston rod and carries a pair of depending fingers Q. These fingers Q are made small enough to enter the grooves 115 in the bed J, and the stroke of the pistons is such that the rear ends of the rails may be forced entirely into the grooves, the fingers Q following them up and entering the grooves for a slight distance, as shown in dotted lines. By this mechanism I secure 120 the pushing of the rails to the full extent desired into the grooves of the bed, and with a positive pressure against the ends of the rails by mechanism which operates rapidly 125 and is under perfect control. Rollers or 130

other antifriction devices may be provided to facilitate the movement of the rails across the bed.

Though I have described with great particularity of detail certain specific embodiments of my invention, yet it is not to be understood therefrom that the invention is limited to the particular embodiments described.

10 Various modifications in detail and in the arrangement and combination of the parts may be made by those skilled in the art without departure from the invention.

What I claim is:—

15 1. A rolling mill for forming or spreading a flange upon an elongated shape having a web and a base, including in combination separable sections for holding such shape in a position transverse to the path of movement so as to carry them laterally under the roll, whereby the pressure of the roll passes from one side to the other of said sections, said sections having overhanging portions, said overhanging portions and the 25 base of the bed, being shaped to tightly engage the top and bottom faces of the base of the shape and to wedge such base between them.

30 2. A rolling mill for forming or spreading a flange upon an elongated shape having a web and a base, including in combination separable sections for holding such shape in a position transverse to the path of movement, said sections having overhanging portions C' with grooved under faces H, and the base of the bed having ribs G, whereby when said sections are brought together with said shape between them the base of the shape is pressed between the groove H 35 and the rib G to curve the same, and at the same time the overhanging edges C' of the sections are firmly supported.

40 3. A rolling mill including in combination

a bed having a groove for receiving an elongated shape, means arranged alongside of 45 said bed for pushing said shape endwise to force it into the groove, and means for forming or spreading a flange on said shape while in said groove.

4. A rolling mill for forming or spreading 50 a flange upon an elongated shape, including in combination a bed having grooves for receiving such shapes, a feeding table arranged alongside of said bed, and means for pushing against the ends of such shapes 55 upon said feeding table and thereby forcing said shapes from the table into said grooves.

5. A rolling mill for forming or spreading 60 a flange upon an elongated shape, including in combination a bed having grooves for receiving such shapes, means comprising a cylinder and piston arranged in line with said grooves for pushing against the ends of such shapes and thereby forcing said shapes 65 into said grooves, and a feeding table adapted to be introduced between said hydraulic means and said bed with said shapes on said table in positions to enter said grooves.

6. A rolling mill for forming or spreading 70 a flange upon an elongated shape, including in combination a bed having grooves for receiving such shapes, a feeding table arranged alongside of said bed, and a pusher bar having a cross head provided with fingers adapted to engage the rear ends of 75 shapes upon said feeding table to push the same endwise into grooves upon the bed, said fingers being adapted to enter said grooves.

In witness whereof, I have hereunto signed 80 my name in the presence of two subscribing witnesses.
